UNITED STATES PATENT OFFICE

98,468

DESIGN FOR A COMBINED CARTON AND TOWEL DISPLAY

Kurt Wandel, New York, N. Y., assignor to The
Rieser Company, Inc., New York, N. Y., a cor-
poration

Application October 22, 1935, Serial No. 59,158

Term of patent 14 years

To all whom it may concern:

Be it known that I, Kurt Wandel, a citizen of the United States, residing at New York city, in the county and State of New York, have invented a new, original, and ornamental Design for a Combined Carton and Towel Display, of which the following is a specification, reference being had to the accompanying drawing, forming part thereof.

The drawing is a view in perspective of a combined carton and towel display embodying my

new design. The shading on the carton and also on the towels therein indicates different tones, shades or colors. The back of the carton is unbroken, there being no opening therein.

I claim:

The ornamental design for a combined carton and towel display substantially as shown and described.

In testimony whereof I have hereunto set my hand on this 14th day of October, 1935.

KURT WANDEL.
